United States Patent Office.

DANIEL S. COLBY AND ROBERT SCORER, OF TROY, NEW YORK.

Design No. 2,723, dated August 6, 1867.

DESIGN FOR THE PLATES OF A PARLOR STOVE.

The Schedule referred to in these Letters Patent and making part of the same.

TO ALL WHOM IT MAY CONCERN:

Be it known that we, DANIEL S. COLBY and ROBERT SCORER, of Troy, in the county of Rensselaer, and State of New York, have invented or produced a new and original Design for Parlor or Heating-Stove Plates, of which the following is a full and exact description, reference being had to the annexed drawings and letters of reference marked thereon, making a part of this specification, in which—

Figure 1 is a perspective view of the bottom plate, and

Figure 2, a perspective view of a door-plate with the door, all of the same stove.

Our said design is composed and arranged of parts, as follows, to wit: The bottom plate A (fig. 1) has, forming its outer edge, the quarter-round moulding *a*, and, next, the half-round bead *b*, which form the edge or border of said plate. *c* and *d* are mouldings, forming the sides and back-base parts of the ash-pit, and the ornamental moulding *e* forms the top part of said pit. *B* is a register-plate, closing the front part of said ash-pit, and has the half-round moulding *f* for its base edge. *C* (fig. 2) is a door-plate, having a scroll ornament, *g*, on its bottom part, and the points *j* arranged on the inclined sides of the doorway. *D* is a door, hinged to said door-plate, and has a scroll ornament, *h*, arranged at its top part, and the ornamental moulding *i* forming the outer edge of said door, the panel of said door being divided by a mullion-moulding into two windows or illuminating spaces, as shown in the drawing.

What we claim as our invention, production, or design, and desire to secure by Letters Patent, is—

The design for stove-plates, as herein described and shown.

D. S. COLBY,
ROBT. SCORER.
